UNITED STATES PATENT OFFICE.

HORACE E. GRANT, OF PITTSBURGH, PENNSYLVANIA.

LIQUID-STORAGE SYSTEM.

1,042,107.

Specification of Letters Patent. Patented Oct. 22, 1912.

Application filed October 12, 1910. Serial No. 566,730.

To all whom it may concern:

Be it known that I, HORACE E. GRANT, a resident of Pittsburgh, in the county of Allegheny and State of Pennsylvania, have invented a new and useful Liquid-Storage System, of which the following is a full, clear, and exact description, reference being had to the accompanying drawings, forming part of this specification, in which—

10 Figure 1 is a sectional elevation of apparatus embodying my invention; Fig. 2 is a side view; Fig. 3 is a vertical section of the measuring and valve portions of the apparatus; and Fig. 4 is a detail sectional 15 view of the valve.

My invention has relation to a storage system for gasoline and other volatile liquids of that class wherein the liquid is forced out of a storage tank or reservoir by 20 means of air pressure.

The object of the invention is to provide means of simple, novel and efficient character whereby the quantity of gasoline delivered may be accurately measured as it is 25 delivered.

Referring to the accompanying drawings, in which I have illustrated the preferred embodiment of my invention, the numeral 2 designates a closed storage tank of the 30 desired capacity, which is preferably buried in the ground, as indicated, and which is provided with an upwardly extending filling neck 3. This neck is preferably provided with a closing cap 4, which can be 35 secured by a suitable lock 5.

6 designates a supplemental tank below the bottom of the main tank with a common separating wall 7. This supplemental tank is of much smaller capacity than the 40 main tank, and is provided in order that a liquid may be forced therefrom by the use of a smaller amount of air than would be possible when forced directly from the main tank, especially after the main tank became 45 partially emptied of its contents. Liquid is admitted from the main tank into the supplemental tank through a suitable valve casing or fitting 8, having one or more lateral inlet openings 9, these openings being 50 arranged to be closed by a suitable check valve when air is admitted to the supplemental tank. This check valve forms no part of the present invention. A liquid outlet pipe 11 is connected to the upper end of 55 the fitting 8, and thence extends upwardly to a suitable valve casing 12, located above

the ground at any convenient point. A short pipe section 13, open at both its upper and lower ends is secured to the lower end of the fitting 8, and extends downwardly 60 into the supplemental tank. The check valve in the fitting 8 is normally open so that liquid can flow freely from the main tank into the supplemental tank, but is closed, as above stated, when the air pressure is admitted to the supplemental tank.

14 is the pipe for admitting air to the supplemental tank and extends upwardly through the main tank and to the valve casing 12, above referred to. The pipe 11 70 serves as the outlet pipe for the gasoline and also leads to the valve casing 12.

In the valve casing 12 is a valve 15 of the turning plug type. This valve is seated in casing 12, and its stem is provided 75 with a suitable actuating lever or handle 15^a, which is preferably arranged to be secured by a suitable lock, as indicated at 16. The valve has at one end portion a cut-away portion or port 17, and at the opposite end 80 portion a port 18.

19 is a gasoline delivery pipe which is arranged to be put in communication with the outlet pipe through the port 17.

20 is an air pump or other suitable source 85 of air pressure, which is arranged to be connected by a pipe 21 through the port 18 with the air pipe 14.

22 is a vent pipe leading from the valve to another vent pipe 23, which is extended 90 downwardly and communicates with the upper portion of the main tank. With the valve in its normal closed position, as shown in Figs. 3 and 4, the vent pipe 22 is connected with the air pipe 14, through the port 18, 95 thereby giving a normally open vent for the supplemental tank. The pipe 23 provides a normally open vent for the main tank.

24 is a measuring vessel of the desired capacity, which is connected in a pipe 25, 100 which leads from the valve 15 to the vent pipe 23. Placed at each side of this measuring vessel is an indicator 25^a, each of which has a passage therethrough in which is placed a vane or paddle 26, mounted on a 105 rocking shaft or axis 27, which has an exterior projected end to which is secured a weight 28.

The operation is as follows: With the valve 15 in the normally closed position 110 shown, all communication is cut off between the pump 20 and supplemental tank, and

the connection between the liquid outlet pipe 11 and the liquid discharge pipe 19 is also closed. When it is desired to obtain liquid from the supplemental tank, the valve 15 is 5 actuated so as to fully open the communication between the pipe 11 and the pipe 25. This movement of the valve also connects the air pump with the pipe 14. Air pressure now flows into the supplemental tank and 10 forces liquid upwardly through the pipe 11, port 17 and the lower indicator 25^a into the measuring vessel 24. The movement of the lower indicator will show that liquid is properly flowing. As soon as the measuring 15 vessel becomes filled, the liquid will rise into the upper indicator 25^a, and thus indicate that fact. If the air pump should be operated after the measuring tank is thus filled, the excess liquid will simply flow into the 20 pipe 23 and back into the main tank. When the measuring vessel 24 has been filled, the valve is given a further movement to connect the measuring tank with the delivery pipe 19, and the liquid flows out of the 25 measuring tank by gravity. When the tank is emptied, the operation is repeated. The lower indicator shows that the measuring tank has been emptied. In the normal position of the valve, as shown in Fig. 3, the port 17 communicates with the pipe 11 to a sufficient extent to permit the vessel 24 to drain. 30 Therefore, no liquid can normally remain in said vessel.

By the apparatus described, I provide a 35 simple and efficient system for the storage and delivery of liquids, particularly gasoline and other volatile liquids, and having means of simple and reliable character by which the exact amount of the liquid delivered is automatically measured.

It will be understood that my invention is 40 not limited in its application to the particular system which I have herein shown and described, since the measuring device which 45 forms the main feature of my invention is applicable to other systems. It will also be apparent that various changes may be made in the details of the valve, in the connection

of the measuring device into the system, and in the form and arrangement of the indicators, without departing from the spirit and scope of my invention, as defined in the appended claims. 50

I claim:

1. In a liquid storage and delivery system, 55 a storage receptacle, an outlet pipe leading therefrom, means for admitting air pressure to the storage receptacle, a valve controlling the outlet pipe, and a measuring vessel arranged to be connected to the outlet pipe 60 through the said valve and having an overflow, together with means operated by the passage of the liquid into said overflow for indicating the filled condition of the measuring tank, substantially as described. 65

2. In a liquid storage and delivery system, 70 a storage receptacle, an outlet pipe leading therefrom, an air pipe communicating with the storage receptacle, a source of air pressure, a liquid delivery pipe, a measuring 75 vessel connected to the outlet pipe and to the delivery pipe, and a single valve member arranged to control the connection of the air pipe with the source of air pressure, the connection of the outlet pipe with the delivery pipe and the connection of the measuring vessel with the outlet pipe, said valve also having a venting connection, substantially as described.

3. In a liquid storage and delivery system, 80 a storage receptacle, an outlet pipe leading therefrom, means for admitting air pressure to the storage receptacle, a valve controlling the outlet and also the air admission pipe, and a measuring vessel arranged to be connected to the outlet pipe through the said 85 valve, said valve when in a position to close the admission of air to the storage receptacle having a drain opening for the measuring vessel, substantially as described. 90

In testimony whereof, I have hereunto set my hand:

HORACE F. GRANT.
